(57) **CLAIM**

I claim the ornamental design for a pet litter box with a paw-cleaning screen.

DESCRIPTION

FIG. 1 is a perspective view of a pet litter box with a paw-cleaning screen of the present application;

FIG. 2 is a left side view of the pet litter box; the right side view being a mirror image of the side shown;

FIG. 3 is a front view of the pet litter box;

FIG. 4 is a rear view of the pet litter box;

FIG. 5 is a top view of the pet litter box; and,

FIG. 6 is a bottom view of the pet litter box.
